UNITED STATES PATENT OFFICE.

FRANK KUHN AND FRANK E. SHAILOR, OF DETROIT, MICHIGAN, ASSIGNEES TO AMERICAN ELECTRICAL HEATER COMPANY, OF DETROIT, MICHIGAN, A CORPORATION OF MICHIGAN.

ELECTRICAL HEATING UNIT.

1,310,994.

Specification of Letters Patent.

Patented July 22, 1919.

Application filed September 9, 1915. Serial No. 49,725.

To all whom it may concern:

Be it known that we, FRANK KUHN and FRANK E. SHAILOR, citizens of the United States of America, residing at Detroit, in the county of Wayne and State of Michigan, have invented certain new and useful Improvements in Electrical Heating Units, of which the following is a specification, reference being had therein to the accompanying drawings.

The invention relates to electrical heating units of that type in which the heat is distributed by radiation from a naked resistor. It is the object of the invention to employ a continuous resistor and at the same time to concentrate the radiation at a plurality of points distributed over an area. To this end the invention comprises the construction as hereinafter set forth.

20 In the drawings:

Figure 1 is an elevation of a portion of the unit;

Fig. 2 is a longitudinal section thereof;

Fig. 3 is a perspective view of the resistor; 25 and

Figs. 4 and 5 are perspective views of the complementary insulator members on which the resistor is mounted.

A is a resistor of any suitable length. 30 B B' etc. are coiled portions of the resistor, each comprising a plurality of convolutions, preferably forming a cone. The portion C leading from the top convolution passes downward through the center of the coil and 35 then laterally at D to the next adjacent coil. E are insulators formed of refractory material, such as porcelain, and which have a conical portion F for receiving the conical coil. This conical portion is slotted at G on 40 one side thereof for the insertion of the portion C of the coil, and at the base of the cone is a flange portion H which has slots I for receiving the lateral portions of the resistor. J is an insulator ring for fitting around the 45 cone F and against the base flange H. This ring J has a projecting portion K of reduced diameter for fitting into an apertured holder plate L, and the member E is also provided with a portion M of reduced diameter for 50 fitting into an apertured holder plate N.

With the construction as described to assemble the unit, the coils B B' etc. are engaged with a series of members E, and the

members J are then placed in engagement therewith, as shown in Fig. 2. The pairs of 55 members are then placed between the parallel holder plates L and N, while the intermediate connecting portions of the resistor are housed between said plates, being spaced therefrom and out of electrical contact. 60 When the current is passed through the resistor, each of the coils will form a glowing point of radiation, and by reason of the engagement of the members E and J displacement is prevented.

65 What we claim as our invention is:—

1. An electrical heating unit, comprising a continuous resistor having a series of spaced convoluted portions and insulators formed of complementary sections engaging 70 each of said convoluted portions directly and clamping the same in position.

2. An electrical heating unit, comprising a continuous resistor having a series of convoluted portions, and insulators for supporting 75 said convoluted portions, comprising a conical base portion and a clamping ring.

3. An electrical heating unit, comprising a resistor having conical convoluted portions with the terminal portion extending 80 through the axis of the convolutions, and an insulator having a portion for fitting within said convolutions slotted to receive said terminal portion.

4. An electrical heating unit, comprising 85 a resistor having a conical convoluted portion with a portion extending axially of the convolutions, an insulator having a conical portion for engaging said convoluted portion slotted to receive said axial portion, and 90 an insulator ring surrounding said conical portion and clamping said resistor thereon.

5. An electrical heating unit, comprising a resistor having a convoluted portion with a terminal portion extending through the convoluted portion and spaced from the convolutions thereof, and an insulator having a portion fitting within said convolutions, slotted to receive said terminal portion.

6. An electrical heating unit, comprising a 100 resistor having a series of convoluted portions, insulators for supporting said convoluted portions, comprising a base portion fitting within the coil and a clamping ring, and spaced members for holding the clamping ring upon the base portion, one of said

spaced members being apertured for the reception of one of the insulators.

7. An electrical heating unit, comprising a resistor having a convoluted portion with a terminal portion extending through the convoluted portion and spaced from the convolutions thereof, an insulator having a portion fitting within said convolutions slotted to receive said terminal portion, an insulator ring surrounding said portion fitting

within the convolutions and clamping said resistor thereon, and spaced members clamping said insulator parts to each other.

In testimony whereof we affix our signatures in presence of two witnesses.

FRANK KUHN.

FRANK E. SHAILOR.
